UNITED STATES PATENT OFFICE.

JOHN JOSEPH O'BRIEN, OF BROOKLYN, NEW YORK.

CHECK PROTECTOR.

1,402,531.

Specification of Letters Patent.

Patented Jan. 3, 1922.

Application filed August 2, 1921. Serial No. 489,245.

To all whom it may concern:

Be it known that I, JOHN J. O'BRIEN, a citizen of the United States, and resident of the city of New York, borough of Brooklyn, in the county of Kings and State of New York, have invented a new and Improved Check Protector, of which the following is a full, clear, and exact description.

My invention relates to check protectors, and aims to provide certain new and useful improvements in connection with a device of this character, and more particularly over the structure presented in my copending application.

More particularly my present invention aims to provide a device of the character stated which may either be carried in the user's pocket or form a part of a writing implement, if this is desired, so that the same will be universally adaptable.

Further it is an object of this invention to provide a check protector which shall be extremely simple in construction and positive in operation, and which also may be used by the operator in a perfectly normal manner.

Further objects of my invention will appear in the annexed specification taken in connection with the drawings which latter illustrate one practical embodiment of the same, and in which:

Figure 1 is a side view of my improved type of check protector and showing the same in use.

Figures 2, 3, 4 and 5 are somewhat diagrammatic views illustrating the construction and disposition of the parts one with respect to each other.

Figure 6 is a sectional side view taken through the protector.

Figures 7 and 8 are sectional views taken along the lines 7-7 and 8-8 and in the direction of the arrows indicated in Figure 4, and

Figure 9 is a sectional view taken along the lines 9-9 and in the direction of the arrows indicated in Figure 6.

Referring now more particularly to Figure 6 it will be seen in the embodiment illustrated that the protector includes three main pieces, to wit, a stem 10 of any desirable shape and material which is slidably encircled by a sleeve 11 preferably having its exterior face knurled as at 12, and a housing 13.

It will be seen that the parts are retained assembled by virtue of the fact that the sleeves 12 carries a pair of pins 15, the former riding in an angularly disposed slot 16 formed in the housing 13 while the latter 60 projects into a slot 17 formed in the stem 10.

Further the stem 10 is provided with a projecting portion 18 the head of which is enlarged as at 19 and carries a pair of spaced ears 20 between which a toothed wheel 21 65 is rotatably mounted. It will be seen that the pin 15 preferably has its inner end extended to project slightly beyond the head 19. This will further act to prevent an accidental detachment of the parts, and it will 70 be understood that upon the sleeve 11 being rotated that any longitudinal movement of this element with respect to the stem 10 will be precluded in that the pin 15 will simply ride within the slot 17.

Further by virtue of the angular disposition of the slot 16, the pin 15 will cause the housing 13 to move longitudinal with respect to the stem 10 and by reason of the fact that the housing 13 is formed with an 80 opening 22 it will be appreciated that this will result in the wheel 21 extending beyond this housing as in Figure 4 when said housing is retracted, and that the wheel 21 will be completely enveloped as in Figures 5 and 85 6 upon the latter being projected. Further in this connection it is to be noted that a rotation of the housing 13 with respect to the stem 10 is prevented in that a longitudinal groove 24 is formed in one of these members, which groove acts as a guide for the pin 25 carried by the second of the same.

To now provide means which will permit of a person utilizing this device in a normal manner it will be seen that the housing 13 90 has its forward end inclined as at 23.

From the foregoing it will be seen, attention being invited to Figure 1, that an operator may hold the protector in a perfectly natural manner, in that it is permissible to 100 actuate the device while the same is held in an inclined position.

Thus all of the objects of my invention as set forth in the preamble of this specification will have been accomplished, and it 105 will be appreciated that numerous modifications of structure might readily be resorted to without in the least departing from the spirit of my invention, which I claim as;

1. A check protector including a stem, a 110

toothed wheel carried by said stem, a housing secured to said stem, and means for effecting a positive projection and retraction of said housing with respect to said stem.

5. 2. A check protector, including a stem, a toothed wheel adjacent the end of said stem, and a housing encircling said stem, said housing being formed with a tapered end portion.

10. 3. A check protector including a stem, a toothed wheel carried by said stem, a housing, and a sleeve encircling a part of said housing and stem, and being connected to these members.

15. 4. A check protector including a stem, a toothed wheel carried by said stem, a housing, and a sleeve partially encircling said housing and stem, said stem being formed with a slot, said housing being formed with

an angularly disposed slot and pins carried 20 by said sleeve and extending into said slots.

5. A check protector including a stem, a toothed wheel carried by said stem, a housing, a sleeve encircling said stem and housing, and means co-operating with said parts 25 for permitting said housing to be moved with respect to said stem when said sleeve is rotated.

6. A check protector including a stem, a head connected to said stem, spaced ears 30 carried by said stem, a wheel rotatably carried between said ears, a housing adapted to enclose said wheel, and ears, and means co-operating with said stem and housing for effecting a longitudinal movement of one of 35 these elements with respect to the second of the same.

JOHN JOSEPH O'BRIEN.
